[57] CLAIM

The ornamental design for a vascular tunneler, as
shown and described.

DESCRIPTION

FIG. 1 is a top plan view of a vascular tunneler in a fully
assembled condition, showing my new design;

FIG. 2 is a bottom plan view thereof;

FIG. 3 is an end elevation as seen in the direction of line
3—3 of FIG. 1;

FIG. 4 is a longitudinal cross-sectional view taken on
line 4—4 of FIG. 3;

FIG. 5 is a top plan view of the outer casing of the
instrument, shown separately for clarity of illustration;
and

FIG. 6 is a top plan view of the inner portion of the
instrument shown separately for clarity of illustration.
